UNITED STATES PATENT OFFICE.

JACQUES ROMANO, OF ROCHESTER, NEW YORK.

POCKET-HUMIDOR.

1,088,369.

Specification of Letters Patent. Patented Feb. 24, 1914.

Application filed September 9, 1913. Serial No. 788,878.

To all whom it may concern:

Be it known that I, JACQUES ROMANO, a citizen of the United States, residing at Rochester, in the county of Monroe and State of New York, have invented a new and Improved Pocket-Humidor, of which the following is a specification:

My invention, while relating to humidors in general, has especial reference to means used in connection with pocket tobacco boxes for keeping the contents thereof in a moist condition; and the objects of the invention are to provide a device for such a purpose that is simple in construction, that can readily be inserted or removed from the cover of an ordinary tobacco box and one that will retain its place when the cover is removed and that will not become dislodged when the box is shaken and is only partly filled with tobacco. I attain these objects by making a device such as illustrated in the accompanying drawings, in which—

Figure 1 is a top plan view of a pocket tobacco box with the cover thereof opened and turned back and with the pad holding device having a pad therein inserted in the cover; Fig. 2, at the top, a vertical sectional view of the parts seen in Fig. 1 but with the cover closed and, at the bottom, a side elevation of such parts; Fig. 3, a plan view of the device and pad therein with parts broken away to bring out more clearly features of construction; and Fig. 4, a longitudinal central sectional view of a box and cover with the humidor device therein.

Similar letters refer to similar parts throughout the several views.

A tobacco box of the ordinary type adapted to be carried in the pocket of the user and having flat sides and rounded ends is shown at B. The cover C engages over the box B, as shown in Figs. 2 and 4, and is hinged to the rear wall thereof by the piano hinge h on the wire or rod w. When the cover of the box is in closed position, the edge of the front wall thereof will engage against the ridge b pressed outwardly from the wall of the box.

A pad A of any suitable absorbent material, preferably felt, is cut to fit within the pad holder or case D in which d² represents the bottom, provided with suitable vent holes o, d the sides and d¹ the ends. This case D has an open top and is of a depth substantially equal to the thickness of the pad A. The outer edge of one of the sides d

of the case D is formed into a longitudinally extending roll e¹ tightly around the central portion p¹ of the wire, as shown, and the other side d has formed along its outer edge 60 a similar roll e but having a slightly greater diameter.

The portion of wire extending outwardly from each end of the bead e¹ is formed into a loop P, such loop portions lying in the 65 same plane with each other and substantially parallel with the bottom d² of the pad holder. The ends of the wire are inserted, from opposite directions, into the ends of the roll e and are free to move longitudinally therein. The loop portions P of the wire thus become springs and when the device is placed in the cover C they engage under tension against the rounded end walls of the cover, holding the device securely in 75 position. If desired, depressions, such as seen at c in Fig. 4, may be formed in the end walls of the cover C, adjacent to the top thereof, into which the springs P may engage, thus still further preventing the device from becoming dislodged. Before inserting the humidor device in the cover the pad A is saturated with water, and for this purpose such pad may be removable from the holder D. 80

It is believed that from the foregoing description of the construction and method of using my humidor device further explanation is unnecessary.

What I claim is:

1. A pocket humidor comprising, in combination with a tobacco box and cover therefor, an absorbent pad, a pad holder adapted to lie within said cover and a wire bent to form two loop portions lying in the same plane and extending outwardly from opposite sides of said holder, the central portion of such wire secured to said holder and the ends thereof movable in engaging means carried by said holder, said loop portions forming springs adapted to engage against opposite side walls of the box cover. 95

2. A pocket humidor comprising, in combination with a tobacco box and cover therefor, an absorbent pad, a pad holder adapted to lie within said cover and a wire bent to form two loop portions lying in the same plane and extending outwardly from opposite sides of said holder, the central portion of such wire secured to one edge of said holder and the ends thereof extended toward each other and longitudinally movable in 100

engaging means formed along the edge of said holder opposite said first named edge, said loop portions forming springs adapted to engage against opposite side walls of the box cover, all substantially as described and for the purpose set forth.

3. A pocket humidior comprising, in combination with a tobacco box and cover therefor, an absorbent pad, a pad holder adapted to lie within said cover, depressions formed in opposite side walls of said cover and a wire bent to form two loop portions lying in the same plane and extending outwardly from opposite sides of said holder, the cen-

tral portion of such wire secured to one edge 15 of said holder and the ends thereof extended toward each other and longitudinally movable in engaging means formed along the edge of said holder opposite said first named edge, said loop portions forming springs 20 adapted to engage in said depressions substantially as described and for the purpose set forth.

JACQUES ROMANO.
